UNITED STATES PATENT OFFICE.

WILLIS J. FISK AND HOMER L. PHELPS, OF LOCKWOOD, NEW YORK, AS
SIGNORS OF ONE-HALF TO THOMAS J. SIMCOE, OF SAME PLACE.

ROTARY ENGINE.

SPECIFICATION forming part of Letters Patent No. 379,385, dated March 13, 1888.

Application filed September 2, 1887. Serial No. 248,660. (No model.)

To all whom it may concern:

Be it known that we, WILLIS JEROME FISK and HOMER L. PHELPS, both of Lockwood, in the county of Tioga and State of New York, 5 have invented a new and Improved Rotary Engine, of which the following is a specification, reference being had to the annexed drawings, forming a part thereof, in which—

Figure 1 is a side sectional elevation of our 10 improved rotary engine, and Fig. 2 is a vertical transverse section of the same.

Similar letters of reference indicate corresponding parts in both views.

The object of our invention is to provide a 15 simple compact rotary engine specially designed to be driven by steam, water, or compressed air.

Our invention consists in the construction and arrangement of parts, as will be herein- 20 after fully described and claimed.

To the cylinder A are fitted the heads B B', bored eccentrically and chambered to receive the ends of the body *a* of the piston C, and provided with boxes D, formed of the upper part 25 *b*, cast integrally with the cylinder-head, and the lower part, *c*, which is removable and adjustable. In the upper part of the cylinder are formed the supply-ports *d* *d'* and the exhaust-port *e*, which communicate with the 30 valve-chest E. The ports *d* *d'* communicate with the cylinder A on opposite sides of the line of contact between the piston C and the inner surface of the top of the cylinder.

The valve-chest E receives steam through 35 the valve F and contains a D-valve, G, mounted on a valve-rod, H, extending through a stuffing-box, *f*, in the side of the valve-chest. The valve G is capable of covering the exhaust-port *e* and one or the other of the ports *d* *d'*, 40 leaving the remaining port, *d* or *d'*, in communication with the valve-chest E.

The body *a* of the piston C is mortised transversely to receive the sliding abutment I, which is formed of three principal sections, *g* 45 *h* *h'*. The central section, *g*, is grooved in opposite edges to receive tongues *i*, formed on the sections *h* *h'*. The sections *h* *h'* are each formed of two parts, *j* *j'*, which are beveled

at their inner overlapping ends to permit of longitudinal expansion of the sections. 50

To the chambers in the heads B B' are fitted the ends of the body *a* of the piston C, and in a circumferential groove in each end of the piston-body is fitted a packing-ring, *k*, which prevents the escape of steam through the journals of the piston. The rings are split to 55 permit them to expand and notched to receive lug-pins *l*, projecting from the body of the piston.

When steam is admitted to the valve-chest 50 E, it enters the port *d* or *d'* and exerts a pressure upon one or the other of the outer sections of the sliding abutment I, while the steam escapes from the opposite side of the piston through the cavity in the valve G and through 65 the exhaust-port *e*. When it is desired to reverse the motion of the engine, the valve G is moved so as to bring the port which before supplied steam to the cylinder into communication with the exhaust-port and to bring 70 the port which before served as exhaust-port into communication with the valve-chest E.

The sections *h* *h'* of the sliding abutment I are held in contact with the inner surface of the walls of the cylinder by steam-pressure 75 and by centrifugal action, and the parts *j* *j'* of each outer section of the abutment are expanded longitudinally by the pressure of steam in the joints between the two parts.

Having thus fully described our invention, 80 we claim as new and desire to secure by Letters Patent—

1. In a rotary engine, the combination, with the cylinder provided with the transverse valve-chest E, supply-ports *d* *d'*, exhaust-port 85 *e*, and reversing-valve G, of the piston-body *a*, provided with a transverse mortise, and the sliding abutment I, formed of the sections *g* *h* *h'*, substantially as described.

2. In a rotary engine, the sliding abutment 90 I, formed of a central section, *g*, grooved in opposite edges, and lateral sections *h* *h'*, fitted to the grooves of the central section, each divided into two parts, *j* *j'*, overlapping each other, as shown, substantially as described. 95

3. In a rotary engine, a sliding abutment

comprising a central section, outer sections at opposite sides thereof, and tongue-and-groove connections between adjacent sides of the said central and outer sections, substantially as set forth.

5. In a rotary engine, the combination, with the cylinder open at its ends, of the heads B B', formed with integral upper journal-box sections, b b, and separate lower sections, c c, bolted to said integral sections, substantially as set forth.

5. In a rotary engine, a cylinder - head, B, formed in a single piece with an upper journal-box section, b, and having an inner concentric recess, substantially as set forth.

WILLIS J. FISK.
HOMER L. PHELPS.
